STEWART R. MCKAY, OF CLEVELAND, OHIO, ASSIGNOR TO THE MCKAY COMPANY, OF CLEVELAND, OHIO, A CORPORATION OF OHIO.

MEANS FOR HOLDING DEMOUNTABLE RIMS ON WHEELS.

1,223,501.

Specification of Letters Patent. Patented Apr. 24, 1917.

Application filed June 13, 1916. Serial No. 103,407.

To all whom it may concern:

Be it known that I, STEWART R. MCKAY, a citizen of the United States, residing at Cleveland, in the county of Cuyahoga and State of Ohio, have invented a certain new and useful Improvement in Means for Holding Demountable Rims on Wheels, of which the following is a full, clear, and exact description.

10 This invention relates to means whereby a tire-carrying rim may be secured upon a wheel in proper relation thereto, and firmly held against movement relative to the wheel while in use, and which will permit the easy 15 removal and replacement of said rim when required.

The primary object of the invention is to enable the rim to be quickly removed and replaced, and to be so firmly held upon the 20 wheel that it can not move relative thereto when in use.

Another object is to do these things by means which do not tend to distort the rim but rather to aid in keeping it from being 25 distorted.

Another object is to procure the proper centering of the rim on the wheel before it is clamped thereon.

The invention consists in the construction 30 and combination of parts hereinafter described and definitely pointed out in the appended claims.

In the drawings, Figure 1 is an elevation showing the outer side of a wheel felly 35 carrying a demountable rim held thereon by the means which constitute the present invention; Fig. 2 is a transverse sectional view in the plane indicated by line 2—2 on Fig. 1; Fig. 3 is a sectional view in the plane of line 3—3 on Fig. 1. The difference between these two figures is that in Fig. 2 the clamp 40 is shown in operative position exerting pressure against the side of the rim, while as shown in Fig. 3 the clamp has been moved 45 to inoperative position where it does not interfere with the removal of the rim. Fig. 4 is an outside view of the clamp, and Fig. 5 is an outside view of one of the plates associated with each clamp.

50 Referring to the parts by reference characters, 10 represents the ordinary felly of an ordinary wheel. 12 represents the metal felly band which is secured upon said felly. At the inner side of the felly are means for 55 engaging the inner side of the demountable

rim 15 for the purpose of serving as the thing or things against which the rim is clamped, and therefore of limiting its inward movement. The drawing shows the felly band as having an annular inclined or 60 substantially conical flange 13. This is an old and good construction, because when the rim is forced inward into engagement with this cone, the part of the rim which engages with it, will be centered thereby.

65 Heretofore these conical flanges have been made complete as shown in the drawing; and they have been made mutilated or interrupted. So far as the present invention is concerned it does not matter which construction is employed, in fact, the primary invention is quite independent of whether the means against which the inner side of the 70 rim 15 be clamped be in the shape of a cone. The cone has, however, known advantages, 75 and therefore its use is recommended.

75 The demountable rim 15 may be of any ordinary construction. It may be split or unsplit; and may have the tire holding channel in its outer periphery of any desired shape. These matters will be determined by the kind of tire the rim is designed to carry. The inner diameter of this rim is greater than the outer diameter of the felly band, but not so great as the outer diameter 80 of a large part of the frustum; wherefore, the rim, adjacent its inner side, will engage the cone, but will not engage the felly band. Preferably the rim will be beveled as at 85 16 for engagement with the cone.

90 The construction to the extent above described is conventional; that is to say, it has been recognized for years as good, and has been largely used in association with means by which to move the rim toward and hold 95 it in engagement with said cone frustum. The means which have been most commonly used are known as wedge clamps. When one of these wedge clamps is driven in the clamping direction it goes between the felly band and the rim, in engagement with both, and not only pushes the rim over against the cone frustum, but it also thrusts the rim radially outward, that is, away from the axis of the wheel. For some reason it has heretofore been thought necessary, or at 100 least preferable, to employ wedge clamps which act in the manner stated. It seems to have been a general belief that unless the rim were so forced outward at intervals, the 105 110

outer side of the rim would not be centered with respect to the wheel, notwithstanding the fact that the inner side of the rim was so centered by engaging a cone. The use 5 of these wedge clamps, however, has long been known to have objectionable features. The radial outward pressure which they exert at intervals upon the rim distorts it from the true circle in which it is made, 10 and in which it should remain. Likewise, they tend to permanently set the rim in this distorted condition; and they tend to increase the distortion as the use goes on. After a rim has been in use some time, 15 secured by these wedge clamps, it is found necessary to drive the clamps in farther. This is because the rim has become permanently distorted; and as the wedges are still farther driven in this distortion is increased. 20

The clamping devices now to be described, in which the present invention is embodied, are constructed upon the theory, which 25 practical experience has shown to be correct, that the use of wedge clamps for the purpose of centering the outer side of the demountable rim is not at all necessary or even desirable, if the inner side of the rim engage with a cone frustum; because in that 30 case both the inner and the outer sides of the rim will be equally well centered. If, now, this rim be held firmly in engagement with the cone frustum by means of laterally pressing clamps, and if suitable means be 35 provided for sustaining the strains incident to use upon the clamps tending to move them radially inward, the rim will remain centered permanently. 40

To hold a centered rim on the wheel, and 45 against any movement relative to the wheel, a plurality of rim clamping devices are employed, preferably six for a medium size automobile wheel. Each of these rim clamping devices includes a bolt 20, a nut 21, a clamp 22, and a clamp sustaining lug 26. Each clamp comprises a jaw portion 22^a 50 and a shank portion 22^b. In the latter is a hole 23 through which the bolt passes. The lug 26, which is fixed to and projects laterally from the face of the felly, also passes 55 into this hole and into engagement with a part of the wall of the hole, so that as long as this engagement between the lug and wall of the hole continues, any radial inward movement of the lug toward the center of the wheel is transmitted to and is resisted by this lug. 60

In the construction shown this lug 26 is 65 an outwardly extended conical boss which is an integral part of a plate 27 that is fixed to the outer face of the felly, and the bolt passes centrally through it. The outer wall of this lug, that is to say, the part thereof nearest the rim, is beveled toward the axis 70 of the wheel. Likewise, the engaging part

of the hole in the clamp shank is similarly beveled. When the lug is conical as shown, the part of the hole in the clamp lug is similarly shaped; and is so placed that when the lug projects into this part of the 75 hole the clamp is held in what may be called the operative position; that is to say, the clamp extends outward to a position such that its jaw may engage the side of the rim. When the clamp is in this operative position and the nut is screwed onto the bolt against the clamp shank, the clamp is made to forcefully engage the side of the rim and move it over into engagement with and hold it in engagement with the cone. 80

The clamp as shown has on its inner surface just inside of the jaw a shoulder 22^c which, when the jaw has been forced into clamping engagement with the side of the rim, goes under the rim and lies as close to 85 its inner periphery as is possible without imparting any outward pressure to said rim, such as might distort it. If the rim in use should slip relative to the clamp it could only move radially inward an almost imperceptible distance before it would engage the said shoulder and be thereby stopped. 90

The hole in the clamp shank as shown is shaped like a buttonhole, that is to say, 95 there is a narrow slot 24 which extends from the round part of the hole, to which the lug is fitted, outward toward the jaw shank, the width of this slot is a trifle greater than the diameter of the bolt, and its outer end, 100 that is, the end adjacent the outer edge of the jaw, is in such relation to said outer edge that when the clamp has been moved radially toward the axis of the wheel until the outer end of the slot rests upon the bolt, 105 the outer end of the clamp will be out of the path which the rim must travel in going onto or coming off of the wheel; that is to say, will be in what may be termed the 110 inoperative position.

The preferable manner of operating these 115 clamping devices is as follows: Assume that a rim is fastened by the described clamping devices on a wheel and it is desired to remove it. One first unscrews the nut associated with that clamp which is for the moment at the top of the wheel. When the nut has been sufficiently unscrewed the clamp will, by gravity, slide down the inclined face of the lug and off of the lug, and then will 120 drop radially toward the axis of the wheel until stopped by the engagement of the outer end of the slot with the bolt. When the clamp is in this inoperative position the nut may be slightly screwed on and thereby the 125 clamp will be pressed against the outer end of the lug, and immovably held between it and the nut. The wheel will now be turned to bring other clamps to the top of the wheel, and these clamps will be similarly 130

operated. When all of the clamps have been moved to and locked in the inoperative position described the rim may be readily taken off. When a rim is replaced another rim 5 will be put onto the wheel while the clamps are in this position. Thereafter one by one the clamps will be moved out into operative position and threaded over the associated lugs, and then the nuts will be screwed up. 10 As a nut is screwed on it will soon reach a position where it will prevent the clamp from moving off of the lug, that is to say, will prevent it from moving from the operative position. By a further screwing on of 15 the lug the clamp will be moved so as to firmly clamp the rim over against the opposed clamping device, namely, the cone. The clamp may be pressed against the rim so hard that any movement of the rim independent 20 of the clamp will be impossible.

Any disposition of the outer side of the rim toward the axis of the wheel will, therefore, be first resisted by the clamp; and the strain will then be transmitted to the lug 25 27 referred to. This lug as stated is formed on a plate, and this is preferably secured to the outer face of the felly band by screws. If some reinforcement were not provided the screws would ultimately take the strain 30 applied to the clamps tending to move them radially inward, and might not be able to withstand them. This reinforcement may be provided by forming each one of these plates with a finger 29 which extends over 35 the felly band into the space between it and the rim and in engagement with the felly band.

These fingers may be made to serve another more or less useful function, that is 40 to say, they may be made of spring metal; and as they pass over the felly band they may from the point at which they engage the felly band extend at an inclination outward, and to positions such that they will 45 engage and press against the inner periphery of the rim. When these spring arms are employed, then when the rim is being put onto the wheel these spring arms will help to center the rim, that is to say, the inner side of the rim will be centered by engaging with the cone while the outer side of 50 the rim will be centered by engagement with these inclined spring arms. These arms will to some extent resist any tendency of the 55 outer side of the rim to move toward the axis of the wheel.

Having described my invention, I claim:

1. The combination of a wheel, a demountable rim therefor, means carried by 60 the wheel to engage said rim and limit its movement laterally in one direction, and a plurality of clamping devices for pressing said rim against said clamping means, each clamping device comprising a clamp having a jaw for engagement with the rim and a

shank through which there is a hole, a bolt carried by said wheel projecting laterally therefrom through the hole in the clamp shank, a nut on said bolt, and a lug fixed to the wheel projecting laterally therefrom into the hole in said clamp shank and into engagement with the outer wall of said hole when the clamp is in operative position. 70

2. The combination of a wheel, a demountable rim therefor, means carried by 75 the wheel to engage said rim and limit its movement laterally in one direction, and a plurality of clamping devices for pressing said rim against said clamping means,— each clamping device comprising a clamp having a jaw for engagement with the rim and a shank through which there is a hole, a bolt carried by said wheel projecting laterally therefrom through the hole in the clamp shank, a nut on said bolt, and a lug fixed to 80 the wheel projecting laterally therefrom into the hole in said clamp shank and into engagement with the outer wall of said hole when the clamp is in operative position, the surface of said lug which engages the wall of said hole being inclined at an angle such that when the clamp is at the top of the wheel and the nut is loosened said clamp will slide down said inclined surface off of the lugs and toward the axis of the wheel. 85

3. The combination of a wheel, a demountable rim therefor, means carried by the wheel to engage said rim and limit its movement laterally in one direction, and a plurality of clamping devices for pressing said rim against said limiting means each clamping device comprising a clamp having a jaw for engagement with the side of the rim and a shank through which there is a hole, a bolt carried by said wheel projecting laterally therefrom through the hole in the clamp shank, a nut on said bolt, a plate fixed to the outer face of the felly of the wheel and having an integral lug which projects outward into the hole in said clamp shank and into engagement with the wall of said hole to thereby hold the clamp in operative position and prevent it from moving radially inward therefrom. 100 105

4. The combination of a wheel, a demountable rim therefor, means carried by the wheel to engage said rim and limit its movement laterally in one direction, and a plurality of clamping devices for pressing said rim against said limiting means, each clamping device comprising a clamp having a jaw for engagement with the side of the rim and a shank through which there is a hole, a bolt carried by said wheel projecting laterally therefrom through the hole in the clamp shank, a nut on said bolt, a plate fixed to the outer face of the felly of the wheel and having an integral lug which projects outward into the hole in said clamp shank and into engagement with the wall of said hole to 110 115 120 125 130

thereby hold the clamp in operative position and prevent it from moving radially inward therefrom, and said plate being formed with an integral finger which extends over 5 and into engagement with the outer periphery of the wheel.

5. The combination of a wheel having adjacent its inner side an outwardly inclined 10 conical flange, a demountable rim adapted to engage said flange and be thereby centered, a plurality of inclined spring arms 15 fixed to the wheel and extended over the periphery thereof and between said periphery and demountable rim and into engagement with the latter, and clamping devices for forcing said rim toward and holding it in engagement with said conical flange.

6. The combination of a wheel, a felly 20 band upon said wheel having at its inner side an outwardly inclined conical flange, a demountable rim which may engage said conical flange and thereby be centered in the plane of said engagement, and a plurality 25 of clamping devices each comprising a clamp having a jaw for engagement with the side of the rim and a shank through which there is a hole, a bolt carried by said wheel projecting laterally therefrom through the hole in the clamp shank, a nut on said bolt, a 30 plate fixed to the side of the wheel formed with an integral outwardly projecting inclined conical lug which when the clamp is in operative position goes into the hole in said clamp and engages the wall of said

hole and prevents the clamp from moving radially away from said operative position and said plate being also formed with a finger which project over and engages the felly band.

7. The combination of a wheel, a demountable rim therefor, means carried by the wheel to engage said rim and limit its lateral movement in one direction, and a plurality of clamping devices, each consisting of a clamp having a jaw for engagement with the rim and a shank in which there is a radially elongated hole, a bolt carried by said wheel and projecting laterally therefrom through the hole in the clamp shank, a nut on said bolt, and a plate fixed to the side 45 of the wheel having an outwardly projecting lug formed with a beveled surface that engages a part of said clamp when the latter is in operative position and prevents radial movement away from said operative position, the inclination of said clamp-engaging surface being such that when the nut of that clamping device which is at the top of the wheel is unscrewed the associated clamp will slide by gravity off of said lug and toward 50 the axis of the wheel into inoperative position.

In testimony whereof, I hereunto affix my signature in the presence of two witnesses.

STEWART R. MCKAY.
